United States Patent Office.

GEORGE S. FAULKNER, OF INDIANAPOLIS, INDIANA.

Letters Patent No. 99,177, dated January 25, 1870.

IMPROVEMENT IN LOOM.

The Schedule referred to in these Letters Patent and making part of the same.

I, GEORGE S. FAULKNER, of Indianapolis, in the county of Marion, and State of Indiana, have invented certain Improvements in Drop-Box Motion of Looms, of which the following is a specification.

Nature and Objects of the Invention.

This invention relates to the drop-box movement of looms, having for its object to communicate positive motion to the boxes, as controlled by a pattern-chain or cylinder; and

It consists in operating the pattern-chain by means of a bifurcated lever, between the arms of which an eccentric on the lower shaft of the loom revolves, and imparts a vibratory motion, one arm of the bifurcated lever being connected, by a bar, to one arm of an elbow-crank, to the other arm of which is attached a pawl that actuates a ratchet attached to the pattern-cylinder.

Description of the Accompanying Drawings.

Figure 1 is an end view of the loom-frame, having my improved mechanism for operating the drop-boxes applied thereto; all the other parts of the loom being left off, to show the drop-box mechanism more clearly.

Figure 2 is a side elevation of the same end of the loom.

Figures 3 and 4 are front and edge views, respectively, of the bifurcated lever D D' detached, with a four-pointed cam, that it is designed to substitute for cam F, on the bottom shaft, in order to operate the boxes, to accommodate them to a pick-and-pick motion of the shuttle.

A is the frame of the loom; B, the lay; and C, the drop-boxes, all constructed and arranged in substantially the usual manner.

In order to communicate positive motion to the shuttle-boxes, I construct a bifurcated lever, D D', having its fulcrum on a stud-pin, E.

Vibratory motion is communicated to this lever by an eccentric, F, on the lower or bottom shaft G of the loom.

From the upper end of the long arm D', a connect-

ing-rod, H, extends, to one arm of an elbow-crank, I, pivoted on the same shaft with the pattern-cylinder J,

To the other arm of the elbow-crank I, a hooked pawl, K, is attached, which engages with the ratchet L, shown in dotted lines, fig. 1, and imparts intermittent rotary motion to the pattern-cylinder J.

The pins a, in the pattern-cylinder J, operate the lever M, and the latter being connected, by cord N, to a pawl, O, attached to the long arm of bifurcated lever D D', lowers the pawl to engage with, or raises it to be disengaged from the ratchet P, shown in dotted lines in fig. 1, on the cam-shaft Q.

The cams R, on cam-shaft Q, actuate lever S, to raise and lower the boxes C.

It will be readily understood, by those conversant with looms, that with this arrangement, the pattern-cylinder J is actuated to control the movement of the drop-boxes C, and that the only change in the movement of the boxes required, to use various-colored thread in weaving any variety of pattern, is to change the eccentric F to one like that represented in figs. 3 and 4, by which the movement of the bifurcated lever is doubled.

In order to double the movement of the drop-boxes, the two arms of the bifurcated lever D D' may be made as shown in figs. 3 and 4, so that when used, as shown in figs. 1 and 2, the eccentric F will have to be made wide on the face.

Claim.

I claim, as my invention—

The bifurcated lever D D', and rod H, connecting said lever with the crank I, and the eccentric F on the shaft G, arranged to give positive motion to the pattern-cylinder or chain J, in combination with the pawl O, attached to the lever D D', and the cord N and lever M, for giving the required motion to the cam-shaft Q, all arranged and operating substantially as and for the purpose set forth.

GEORGE S. FAULKNER.
